CLAIM

The ornamental design for a user interface for a portion of a display screen, as shown and described.

DESCRIPTION

FIG. 1 is a front view of a user interface for a portion of a display screen showing my new design; and,

FIG. 2 is a front view of a second embodiment thereof.

The broken line drawing of a portion of a display screen is for illustrative purposes only and forms no part of the claimed design.

1 Claim, 2 Drawing Sheets

FIG. 1

FIG. 2
